Abraham T. Missell, of Oxford, N. Jersey

Letters Patent.

The schedule referred to in these Letters Patent, and making part of the same, containing a description in the words of the said Abraham T. Missell himself of his improvement in the Double Lifting Pump.

Be it known that I, Abraham T. Missell of Oxford in the County of Warren and State of New Jersey, have made an improvement in the Double Lifting Pump, which is described as follows, reference being had to the annexed drawings of the same making part of this specification.

This Pump consists of two vertical tubes A. B. cast together, having a plate C, with flanges, at the top, and a plate D, at the bottom, which close their ends, secured by screw-rods and nuts E. In the upper plate are cavities F, in which the ends of the vibrating lever work. In the lower plate is an aperture G, for the admission of water to valves. Another plate H, is placed across the pump inside with cavities, or depresions, in which the ends of the vibrating lever work in descending. In the bottom of each tube is a valve I. J. opening inwardly. Below the middle plate is a rectangular chamber, K, formed by two partitions, L. M. in which are two other valves, N. O. opening toward the center of this chamber. The spout P, is placed in this chamber. In the tubes are two lifting valves Q. R. attached to the ends of rods, S. T. bent at their ends and passing over pulley U. U. in the ends of the vibrating lever W, which lever is fastened to an axle X, turning in openings in the top of the pump by a lever or handle Y, on the end of the axle.

The pump is made principally of cast and wrought iron.

By moving the handle to the right the valve P_1 is raised which creates a vacuum in the lower end of the tube AB , the water at the same time rushes through the valve S , to fill the vacuum. Then by moving the handle to the left, the valve P_1 is depressed, which opens it whilst the water rushes through; then by moving the handle again to the right, the water above the lifting valve P_1 , is raised and forced through the valve AB into the chamber BC , from whence it is discharged through the spout P . Whilst this operation is going on a similar but alternate operation is performing in the opposite tube. Thus, by alternately moving the handle to the right and left, a constant stream of water is kept flowing through the spout.

What I claim as my invention, and which I desire to secure by Letters Patent, consist in the combination and arrangement of the several parts of the Double Lifting Pump as before described, made principally of Cast Iron.
